MUG

Paul Davis, Swampscott, Mass., and Clara Virginia Eicholtz, Midland, and Bertrand N. Trombley, Birmingham, Mich., assignors to Sweetheart Plastics, Inc., Wilmington, Mass.

Filed Jan. 28, 1972, Ser. No. 221,850

Term of patent 14 years

Int. Cl. D7—01

U.S. Cl. D44—9 A

FIG. 1

FIG. 2

FIG. 3

FIG. 4

FIG. 5

FIG. 6

FIG. 1 is a side elevational view of a mug showing our new design;

FIG. 2 is an end elevational view, looking from the right of FIG. 1;

FIGS. 3 and 4 are top and bottom views thereof;

FIG. 5 is an enlarged cross-sectional detail view taken on section line 5—5 of FIG. 1; and

FIG. 6 is an enlarged cross sectional view of the handle taken on section line 6—6 of FIG. 1.

We claim:

The ornamental design for a mug, as shown.
